UNITED STATES PATENT OFFICE.

CHARLES R. COLT, OF BROOKLYN, NEW YORK, ASSIGNOR TO WILLCOX & GIBBS SEWING MACHINE CO., OF NEW YORK, N. Y., A CORPORATION OF NEW YORK.

POWER TRANSMITTER.

Application filed February 20, 1926, Serial No. 89,819. Renewed August 6, 1928.

In the use of sewing machines in garment manufacturing establishments it has been customary to arrange said machines in rows upon long tables known as power-tables, each machine being belted to its own individual friction clutch power transmitter and the latter being mounted under the table and controlled by the operator of the machine through means such as a foot 5 treadle, knee lever, or the like, to throw the friction clutch in or out to start and stop and control the running of the sewing machine at the will of the operator. The several power transmitters so used have 10 received their power from a line shaft running lengthwise of the table, or more recently have each been combined with an individual motor, usually an electric motor, thus providing each sewing machine with 15 its own individual combined motor and power transmitter, or what may be termed its unitary motor and power transmitter mechanism. It has also become the practice to employ sectional power-tables with 20 one sewing machine to each section and mounted on top thereof and the combined motor and friction clutch power transmitter unit which goes with that particular sewing machine mounted beneath the top of the 25 table section, whereby one section may be employed as an individual separate power-table, or any desired number of sections may be fitted and secured together end to end to 30 thus constitute an extended multi-section 35 table.

The present invention relates to power transmitters and especially has in view combined electric motor and friction clutch power transmitter units particularly adapted 40 for use in conjunction with sewing machines under conditions such as above indicated.

It is common in friction clutch power transmitters, and particularly those used in conjunction with sewing machines to hold 45 the clutch members in gripping engagement, while they are transmitting power, by continued pressure of a non-rotating part or element against a rotating part or element. This produces end thrust with resulting 50 continued friction between rotating and non-rotating parts which friction must be constantly overcome by the driving power while the transmitter is communicating motion to the machine with which it is associated. The 55 additional load incident to such friction re-

quires and consumes additional driving power over what would be sufficient if said friction were absent. Particularly in the case of a combined electric motor and power transmitter unit employed to drive a single 60 sewing machine the elimination of such friction and consequent reduction of load will not only effect a saving in power consumption, but will also make possible the use of less powerful and expensive motors. 65

Objects of the present invention are the elimination or approximate elimination of the aforesaid friction of the end thrust and pressure upon each other of relatively fixed and rotating parts resulting in said friction, 70 the material saving in power consumed by the elimination of said friction, and the incidental possibility of using less powerful and expensive motors than required when 75 said friction is present.

A further object is the elimination of end thrust upon the armature shaft of the motor while the transmitter clutch is in action, whereby the armature may operate in its proper normal and natural position in its 80 field free of end thrust tending to displace it and thereby reduce the power or efficiency of the motor. In other words, the object is to leave the armature sufficient freedom of endwise movement automatically properly 85 strained to position itself or float in its field unrestrained by end thrust upon its shaft.

Further objects are the provision of a power transmitter in which both the driving and driven clutch elements are entirely 90 supported by the driving shaft of the transmitter and held in gripping engagement without imposing end thrust upon said shaft and without pressure of a fixed part against a rotating part to hold the clutch elements in 95 gripping engagement; in which while said elements are in clutching engagement they rotate with the shaft as a unit and without support other than that afforded by the shaft, thus minimizing bearings requiring 100 alinement; in which the driven clutch element is positioned and gripped between two axially relatively movable and separate parts or sections of a two-part driven clutch element; in which said two parts of the 105 driven clutch element are drawn together by spring pressure to grip the driving element between them; in which the driving clutch element while rotatable with the driving shaft is at the same time movable longi- 110

tudinally thereof to accommodate itself to clutching engagement with the driven clutch element; in which the positions of the drive pulley of the transmitter and its belt are constant and not shifted in moving the friction clutch members into and out of gripping engagement, thereby constantly maintaining fixed and true alignment of said pulley with the machine to which power is transmitted and avoiding crooked running of the belt and incidental wear upon the belt and mechanical parts and resulting difficulties; in which the drive pulley of the transmitter is fixedly associated with one part of a two-part driven clutch element and a brake member is fixedly associated with the other part of said driven clutch element with said last-named part shiftable either to cause its brake member to cooperate with another brake member or to cause the two parts of the driven clutch member to coact with the driving clutch member; in which the pulley of the transmitter may be quickly removed from its operative position through a slot or opening in the casing wall and if desired replaced by one of different size, all without disturbing other parts of the mechanism; and in which wear of the clutch and brake surfaces is compensated for by the relative movement of such parts and no adjustments for such wear required—all of these objects applying particularly where the driving shaft is the armature shaft of the motor of a combined motor and power transmitter unit.

Further objects of the invention are the minimization of sidewise stresses upon the motor shaft and its bearings and the obtaining of as near as possible a direct drive from the motor to the machine being driven, and to these ends locating the pulley of the transmitter near the source of power by shortening to an approximate minimum the distance between the end of the motor and the pulley or the plane in which its belt operates and by locating said pulley on the motor shaft between the motor and the clutch elements supported on said shaft.

Further objects of the invention are the provision of a combined motor and transmitter unit in which a sectional casing encloses the motor and transmitter including the rotary clutch elements and pulley of the latter with the provision of a slot or opening through the casing wall for a belt from said pulley; and the shortening of the length of the unit to an approximate minimum and otherwise forming it into a compact structure capable of being readily mounted under either a flat-top or trough-top power-table or section of such a table and accommodated by the space there available with the pulley of the transmitter directly in the vertical plane of the pulley of the sewing machine and without crowding

or encroaching upon the knee and leg space of the operator or projecting beyond the outlines of the table or table section.

The aforesaid and still other objects and advantages hereinafter explained or apparent from the detailed description and drawings are attained by this invention and by the now preferred mechanical embodiment thereof illustrated in the accompanying drawings, wherein

Fig. 1 is a part top plan view and part horizontal sectional view on line 1—1 of Fig. 2, showing the invention embodied in a combined motor and friction clutch power transmitter mechanism or unit;

Fig. 2 is a front elevation with parts of the mechanism shown in vertical section;

Fig. 3 is a detail sectional view through a portion of the housing or casing on line 3—3 of Fig. 1 and showing one of the bolts by which three of the sections of the casing are secured together;

Fig. 4 is a detail view of the coiled spring which normally holds the clutch members out of engagement;

Fig. 5 is an end elevation from the right of Fig. 2;

Fig. 6 is a vertical section on line 6—6 of Fig. 2;

Fig. 7 is a vertical sectional detail view on line 7—7 of Fig. 1;

Fig. 8 is a front elevation and Fig. 9 is an end elevation from the right of Fig. 8 of a double-sided trough-top power-table of standard type for power sewing machines, showing a sewing machine mounted on the top of one side thereof with the unitary power mechanism of Figs. 1 and 2 mounted on the under side of the table in proper operative relation to the sewing machine; and

Fig. 10 is a detail view partly in section showing a modified arrangement in which the driving shaft of the transmitter may be one section of a shaft common to a number of transmitters.

The enclosing casing is made in four separable sections; beginning at the left, Figs. 1 and 2, there is the motor cap section 20, then the motor frame section 21, then the extension section 22, and finally the transmitter cap section 23. The edge of cap section 20, at the open side of that section, accurately fits or telescopes into an interior groove 24 around the edge of the left-hand open end of section 21 and firmly seats against the upright end wall of said groove, thereby insuring proper alignment in the fitting together of these sections. At its left-hand open end the extension section 22 similarly fits or telescopes into an interior groove 25 around the edge of the right-hand open end of section 21 and firmly seats against the upright end wall of said groove, thereby insuring proper alignment in the fitting together of these sections. Four bolts 26, Figs. 130

1 and 3, each having a screw-head at one end and at its other end engaged by an elongated screw-headed nut 27, secure together the three casing sections 20, 21 and 22. These bolts will be again referred to later. Opposing flat surfaces, extending approximately half-way around the open right-hand end of casing section 22 and the open end of cap section 23, accurately seat 10 together as shown at 27 in Fig. 1. Two dowel pins 28, 28 determine the relative positioning in which these two casing sections 22 and 23 are secured together by three screws 29. Around the other half of their circumference or periphery the edges of these two casing sections 22 and 23 are recessed to stand apart from each other thus to form a slot or opening 30 through the wall of the complete casing to accommodate the passage 20 of the driving belt which runs from a pulley within the casing to a pulley on the sewing machine or other mechanism to which power is to be transmitted, this slot being also of a size and location permitting removal there- 25 through of said first-named pulley as well as the introduction therethrough of another pulley of different size to take the place of the one removed, as presently more fully explained. An upstanding bracket extension 30 31 on motor casing section 21 has three seats 32 triangularly positioned with respect to each other and adapted to bear against the bottom surface of a power-table. Screw-headed bolts 33 pass downwardly through 35 the table top, as shown in Fig. 2, and into interiorly screw-threaded openings in the seats 32, thereby securing to the table the complete casing and the parts mounted there-in and thereon and constituting the only 40 means for supporting the same from said table. The use of three seats 32, or in other words what might be called a three-point contact of the bracket 31 with the surface of the table, has the advantage of assuring a firm engagement even if the surface of the 45 table happens to be uneven.

The electric motor may be of well-known standard construction having a field 35 and an armature 36 both shown in dotted outline in Fig. 2. As shown in Figs. 2 and 3, the field 35 is held between nuts on the four previously mentioned bolts 26. Said bolts being screw-threaded throughout their length, the position of the nuts and hence 50 the position of the field may be adjusted longitudinally of the axis of the armature shaft. The motor has a specially constructed armature shaft 37 supported at one end of the motor in a bearing 38 in the cap section 20 of the casing and at the other end of the motor in a bearing 39 supported in a web or partition 40 preferably formed or cast as an integral part of the casing section 22. The starting and stopping switch of the motor is shown at 41 in Fig. 2. An oil cup 45

to the top of bearing 38, a similar oil cup 46 connecting by pipe 47 to the top of bearing 39, depending oil cups 48 and 49 for said bearings, respectively, and associated lubricant passages, all as best shown in Fig. 2, 70 are of well-known standard construction. Oil cup 49 is put in place through an opening 50, Fig. 2, in the bottom wall of casing section 22, and may be removed through the same opening. The shaft 37 has slight end- 75 wise freedom of movement in bearings 38 and 39 to permit its armature 36 sufficient endwise movement to assume accurately and automatically its normal natural magnetic position relative to its field, or in other words, to permit the armature to center or 80 position itself automatically and accurately relative to its field and thereby yield maximum power for current consumed. The armature shaft 37 extends to the right beyond bearing 39, this extension of the shaft including three stepped-down portions 55, 56 and 57 of successively decreasing diameters and with a screw-threaded part 58 between said portions 55 and 56. A drive pulley 60 having a peripheral belt groove 61 is rotatably supported on the shaft 37 by a ball-bearing of suitable preferably standard construction including inner and outer ball race sleeves 62 and 63 and interposed balls 64. Sleeve 62 fits the portion 55 of said shaft and is clamped against a shoulder about the shaft at the end of said portion 55 by a clamp ring 65 having an interior screw-thread engag- 90 ing the threaded part 58 of the shaft. 100 Sleeve 63 fits in a circular chamber or recess in pulley 60 and is clamped and held therein by an exteriorly screw-threaded clamp ring 66 engaging a screw-thread around the interior of the recess in the pulley, said ring 66 being thus positioned concentric to ring 65, as clearly shown in Fig. 1. Drive pulleys of varying sizes are used in transmitters for sewing machines, the size used depending upon the particular conditions encountered, 105 such as the size of the pulley on the sewing machine, the speed desired, etc. The sizes of such drive pulleys commonly run from two and one-quarter inches up to six inches. The drive pulley 60 represents one of the 115 smallest diameter required. The drawings show mounted on and about the pulley 60 another pulley 70 of larger diameter and for which may be substituted still other similarly constructed pulleys of either larger or smaller diameters. As best shown in Figs. 1 and 6, pulley 70 is formed in two semi-circular sections or halves which fit together around pulley 60 and also closely fit in and between the side walls of a peripheral groove of said 120 pulley 60, the two sections of pulley 70 being secured together and clamped to the pulley 60 by two screws 71. The two sections of pulley 70 may be introduced and secured in place, and also removed, through the slot 130

30 of the casing wall and without disassembling or disturbing other parts of the mechanism.

75 is what may be termed the drive pulley 5 friction disk; it is located at the right side of said pulley 60 and is preferably an integral flanged part thereof. A circular concentric groove 76 in the right-hand flat face of disk 75 receives a friction leather ring 10 77 held against longitudinal movement in said groove by pins such as 79, Fig. 1. 80 is a companion disk to disk 75 and is entirely supported by and from the latter on three headed studs 81, Figs. 1 and 7, symmetrically and equi-distantly spaced around and near the peripheries of disks 75 and 80 15 parallel to the axis thereof which axis coincides with the axis of the shaft 37. Each stud 81 passes through an opening in disk 20 80 with a sliding fit and then into an opening in disk 75 where it is rigidly secured by a set-screw 82. Around each stud 81 there is a coiled spring 83, or what may be called a clutch compression spring, bearing at one 25 end against the head of the stud and at its other end against the flat surface of disk 80, the tension of these springs thus constantly tending to slide disk 80 along its supporting studs 81 toward the companion disk 30 75. A circular concentric groove in the left-hand flat face of disk 80 receives a friction leather ring 84 held against longitudinal movement in said groove by pins such as 85, leather ring 84 being thus positioned in 35 position to leather ring 77. The two disks 75 and 80 constitute together a two-part driven clutch member with the drive pulley 60 (or 70 as the case may be) fixed to and rotatable therewith. 90 is the driving 40 clutch member in the form of a circular disk or wheel carried by shaft 37 and positioned between the disks 75 and 80 which as before stated constitute the driven clutch member. Disk 90 has flattened surface portions at both 45 sides thereof for making frictional clutching engagement with the leather rings 77 and 84 respectively. Disk 90 has in its hub three key-ways slidably engaged by three keys 91 respectively, each key making tight 50 engagement in a recess in the portion 56 of shaft 37. Disk 90 is thus rotated with shaft 37 while also free to shift or slide longitudinally along the portion 56 of said shaft.

The disk 80 of the two-part driven member of the clutch is shown as integral with and located at the left-hand end of a hollow hub portion 95. At the other or right-hand end of said hub portion there is an integral annular flange 96 constituting one member 60 of a friction brake, the inner cupped or frusto-conical face of said flange being opposed to a friction brake leather 97 seated in a circular recess around the inner surface of the end wall of cap section 23 of the casing. When the springs 83 have moved the

disk 80 toward the left clutching the disk 90 between the disks 75 and 80, in the position in which these parts are shown in Fig. 1, and thus driving disks 75 and 80 from disk 90, the brake member 96 stands out of engagement with the leather 97 constituting the other brake member, as also shown by the position of the parts in Fig. 1. But normally these parts are held in braking engagement, with the driving and driven 75 clutch members out of engagement, by means which will now be described.

A hub-like projection or boss 100 on the closed end of casing cap section 23 has therethrough a screw-threaded opening 80 through which projects what may be termed a rotatable clutch control screw or member 101 threaded on its exterior for engagement with the threads of said opening. At its inner cylindrical end said rotatable member 101 loosely passes through the hub portion 95 of the combined clutch and brake member and has at its extreme end a head or flange 102 loosely and movably fitting within the hub opening or chamber. A ball thrust-bearing 103 of standard construction encircles the inner end of rotatable clutch control member 101 between the head 102 thereof and a thrust-bearing washer 104 seated against a shoulder around the interior of the hub portion 95. The inner end of clutch control member 101 is axially hollowed or recessed to receive a bearing-sleeve 105 and the end portion 57 of the armature shaft which engages in said bearing-sleeve, 100 the end of said shaft thus serving to rotatably support, center, and guide the inner end of the rotatable clutch control member 101. An axial lubricant passage 110 through clutch control member 101, Fig. 1, 105 leads from a grease cup 111 on the outer end of said member to the chamber at its inner end, and from the latter there is an axial passage 112 through shaft 37, shown in dotted lines in Fig. 1, from its right-hand end to transverse passages 113 leading to the ball-bearing for pulley 60. Other transverse lubricant passages 114 lead from passage 110 to the ball thrust-bearing 103. 110 is a lever arm having at one end a hub or boss 121 having an opening therethrough in which the outer cylindrical end of the rotatable clutch control member or screw 101 fits and is rigidly secured by two set-screws 122, Figs. 1 and 9. A coiled spring 123 115 (Fig. 4) encircles the projecting hub 100 on casing cap section 23 and also the adjacent hub 121 of said lever 120, the inner end of said spring at 124 being bent parallel to the axis of the spring and adapted to engage in 120 any one of a series of openings or sockets 125 in the end-wall of casing cap section 23, four of such sockets being shown in the drawings, Figs. 1 and 5. The tension of spring 123 is determined by the position of 130

the particular socket 125 in which the end 124 of the spring is engaged. The other end of spring 125 is bent to form a hook 126 which is engaged around the upper edge of lever 120 adjacent hub 121 thereof. A link 127 connects the outer end of lever 120 to the upper end of a lever or rock arm 128 fastened at its other end by a set-screw 129 on the end of a rock shaft 130 where said shaft projects beyond one of its supporting bearings through the outer end of a bracket arm 131. Said bracket arm 131 depends in a forwardly inclined direction from the end cap section 23 of the casing with which said bracket arm is preferably integrally cast. At its other end the shaft 130 projects through and has its bearing in a boss or enlargement 132 (Figs. 1 and 6) on the edge of casing section 22, a lever arm 133 being secured on the projecting end of said shaft by a set-screw not shown but similar to set-screw 129 at the opposite end of the shaft. From the outer end of lever arm 133 an adjustably extensible connection rod 134 extends downward to a treadle 135 shown in Figs. 8 and 9.

5 of said member upon the balls of the thrust-bearing 103 and thus leaving the disk 80 of the two-part driven clutch member free to be acted upon by the three coiled springs 83. Said springs are thus enabled to shift 70 the disk 80 toward the disk 75, thereby firmly clamping or clutching between said disks the driving clutch member or disk 90 and also drawing the brake member 96 away from engagement with the other brake 75 member 97. This position of the parts with the clutch thus in action and rotating the drive pulley 60, or 70, and the brake out of action, is shown in Fig. 1. To stop the machine the operative releases pressure on the treadle, whereupon the spring 123 reacts and by its expansion rotates the clutch control screw member 101 counter-clockwise. Such rotation also moves said clutch control member 101 endwise toward the right in 85 Fig. 1 by reason of its screw-threaded engagement through the casing boss or hub 100. By such rotary and endwise movement the clutch control member 101, and the head 102 thereof acting through the ball thrust-bearing 103, slide the clutch disk 80 along 90

In operation, electric current is turned on at the switch 41 (Fig. 2) and the motor thus set in operation to rotate the armature shaft 37. To transmit driving power from said shaft to the sewing machine the operative depresses treadle 135 and keeps it depressed as long as it is desired to continue the running of the sewing machine. Depression of the treadle moves the connecting rod 134 and the lever arm 133 downward. This rotates rock shaft 130, thereby swinging the lever arm 128 at the other end of said shaft upward and forward toward the left in Figs. 5 and 9, and through the link connection 127 rotating the lever arm 120 and with it the clutch control screw 101 in a clockwise direction as viewed in Fig. 5, such movement being in opposition to the resisting tension of the coiled spring 123 and acting to increase the tension thereof. The clutch control member 101, by such rotation and its screw-threaded engagement through the casing wall, is moved inward to the position in which is is shown in Fig. 1, thereby releasing all pull or pressure of the head 102 into engagement to arrest rotation of the two-part driven clutch member 75, 80 and associated drive pulley and machine to which the latter is belted. The driving clutch member or disk being thus released from the clutching engagement of the disks 75 and 80 continues to rotate idly until the operative again throws the clutch into action by depressing the treadle.

erative by depression of the treadle does not apply power which itself presses the clutch members into engagement, as is usually the case in sewing machine power transmitter 5 clutches, but merely brings about the condition which enables the spring means (including springs 83) to apply that power. Hence strain of excessive power applied by the operative does not fall upon the clutch members, but upon other parts of the mechanism where it is less likely to cause damage.

If not desired to employ an individual motor to each transmitter, but to drive a 10 number of sewing machines from a common 15 source of power distributed by line shaft and belting for example, a suitably belt-driven pulley could be substituted for the electric motor shown in the accompanying drawings said pulley being fixed to the shaft 20 37 to continuously rotate the same. Or the shaft 37^a may be extended entirely through the clutch control screw or member 101^a in the manner illustrated in Fig. 10, and be provided at both ends with couplers 150 25 joining it to other shaft sections, a number of such coupled together sections constituting a line shaft applying to the desired number of individual transmitters.

While it will be readily understood that 30 the mechanism described in detail realizes the objects and advantages hereinbefore set forth, reference is here again made to the following characteristics thereof: Power transmitters of the type under consideration 35 commonly employ two shafts or shaft sections for the clutch elements respectively, these shafts and their bearings requiring alinement. In the present structure only one shaft or shaft section is employed, that is to say, the disk or part 75 of the driven 40 clutch member is rotatably supported on armature shaft 37 and in turn supports the other disk or part 80 of said clutch member by the studs 81; the driving clutch element 45 90 is also carried by said shaft and all of these parts as well as the pulley rotate with said shaft when the clutch is "in". The pulley 60, or 70, of the transmitter is located 50 on the shaft immediately adjacent the motor and between it and the clutch elements on said shaft, thus approximating a direct drive from the motor to the sewing machine. The position of the pulley 60, or 70, remains 55 constant whether rotating or not; that is to say, it is not shifted when the transmitted clutch is thrown in and out. Strain and wear upon the belt and other parts are thus avoided. When the clutch parts are in grip 60 and rotating with the motor shaft, said shaft is entirely free of end thrust and there is no condition of a stationary part pressing 65 against a rotating part with consequent friction and resulting load upon the motor. By such elimination of end thrust and friction and reduction of load, a substantial and

large saving in power consumption is effected and it is possible to employ less powerful and less expensive motors in combined motor and transmitter units. Furthermore, the armature is free to operate in its natural and proper position in its field and the motor generally to function with maximum efficiency.

As will be apparent, the invention is not restricted to the particular structural embodiment thereof illustrated and described, but on the contrary is susceptible of a variety of embodiments all within the definition of the invention given in the claims which follow.

What is claimed as new is:

1. In a power transmitter, the combination of a driving shaft; a driving clutch element actuated by said shaft; a cooperating driven clutch element; means pressing said elements into power transmitting clutching engagement with each other without creating end friction to be overcome by the driving power of said shaft while the transmitter is acting to transmit power; means causing said clutch elements to release their power transmitting clutching engagement with each other and thereby render the transmitter inactive and means under control of an operative for rendering said releasing means ineffective.

2. In a power transmitter, the combination of a driving shaft; a driving clutch element actuated by said shaft; a cooperating driven clutch element; means pressing said elements into power transmitting clutching engagement with each other without pressure of a non-rotating part against a rotating part to maintain such engagement while transmitting power; means for causing said clutch elements to release their power transmitting clutching engagement with each other and thereby render the transmitter inactive and means under control of an operative for rendering said releasing means ineffective.

3. In a power transmitter, the combination of a driving shaft; a driving clutch element actuated by said shaft; a cooperating driven clutch element; means pressing said clutch elements into power transmitting clutching engagement with each other without pressure of a non-rotating part against a rotating part to maintain such engagement while transmitting power and without creating end friction to be overcome by the driving power of the shaft while the clutch elements are in engagement and transmitting power; means for causing said clutch elements to release their power transmitting clutching engagement with each other and thereby render the transmitter inactive and means under control of an operative for rendering said releasing means ineffective.

4. In a power transmitter, the combina-

- tion of a driving shaft; a driving clutch element actuated by said shaft; a cooperating driven clutch element; spring means carried by one of said elements and acting upon the other element to press the two elements into power transmitting clutching engagement; means acting counter to said spring means to cause said clutch elements to release their power transmitting engagement and thereby render the transmitter inactive and means under control of an operative for rendering said releasing means ineffective. 5
5. In a power transmitter, the combination of a driving shaft; a driving clutch element 15 rotatable with said shaft; a cooperating driven clutch element; spring means carried by said driven clutch element and acting upon said driving clutch element to move it axially of said shaft and press it into power transmitting engagement with the driven clutch element; means acting counter to said spring means to cause said clutch elements to release their power transmitting engagement and thereby render the transmitter inactive 20 and means under control of an operative for rendering said releasing means ineffective. 25
6. In a power transmitter, the combination of a driving shaft; a driving clutch element carried by and rotatable with said shaft; a 30 cooperating driven clutch element carried by said shaft; spring means carried by one of said elements and acting on the other element to relatively move and press said two clutch elements into power transmitting 35 clutching engagement; means acting counter to said spring means to cause said clutch elements to release their power transmitting engagement and thereby render the transmitter inactive and means under control of an operative for rendering said releasing means ineffective. 40
7. In a power transmitter, the combination of a driving shaft; a driving clutch element carried by and rotatable with said shaft; a 45 cooperating driven clutch element part journaled and supported on said shaft but fixed against movement axially thereof; a pulley fixedly connected to said driven clutch element part to rotate therewith; 50 spring means carried by said driven clutch element part and acting to press it into power transmitting engagement with the driven clutch element part; and means causing release of said power transmitting 55 engagement of said elements and thereby rendering the transmitter inactive. 60
8. In a power transmitter, the combination of a driving shaft; a driving clutch element carried by and rotatable with said 65 shaft; a cooperating driven clutch element including two relatively movable parts; a pulley fixed to one part of said driven clutch member to rotate therewith; a brake including two cooperating members one of which 70 is carried by the other part of said driven 75 clutch member; spring means carried by said driven clutch element and acting to press the driving and driven clutch elements into power transmitting clutching engagement with each other; and means causing said clutch elements to release their said power transmitting clutching engagement and the brake member on one part of the driven clutch element to engage its cooperating brake member. 70
9. In a power transmitter, the combination of a driving shaft; a driving clutch element carried by and rotatable with said shaft; a 80 cooperating driven clutch element including relatively movable parts one fixed against movement axially of said shaft and the other movable axially of said shaft; a pulley fixed to one of said parts to rotate therewith; a brake including two cooperating members adapted to be moved into and out of engagement with each other one of said members being carried by said part of the drive clutch element which has movement axially of the driving shaft; spring means carried by said driven clutch element and 85 acting on said driving clutch element to press the two elements into power transmitting clutching engagement with each other; and means causing said clutch elements to release their said power transmitting clutching engagement and moving the axially movable part of the driven element to engage the brake member thereof with said cooperating brake member. 90
10. In a combined motor and power transmitter, the combination of an electric motor and its armature shaft; a driving clutch element actuated by said shaft; a cooperating driven clutch element; means pressing said elements into power transmitting clutching 100 engagement with each other without creating end thrust to be overcome by the driving power of said shaft while the transmitter is acting to transmit power; and means causing said clutch elements to release their power 105 transmitting clutching engagement with each other and thereby render the transmitter inactive. 110
11. In a combined motor and power transmitter, the combination of an electric motor and its armature shaft; a driving clutch element actuated by said shaft; a cooperating driven clutch element; means pressing said elements into power transmitting clutching 115 engagement with each other without pressure of a non-rotating part against a rotating part to maintain such engagement while transmitting power; and means causing said clutch elements to release their power transmitting clutching engagement with each 120 other and thereby render the transmitter inactive. 125
12. In a combined motor and power transmitter, the combination of an electric motor and its armature shaft; a driving clutch ele- 130

- ment actuated by said shaft; a cooperating driven clutch element; means pressing said clutch elements into power transmitting clutching engagement with each other without pressure of a non-rotating part against a rotating part to maintain such engagement while transmitting power and without creating end thrust to be overcome by the driving power of the shaft while the clutch elements are in engagement and transmitting power; and means for causing said clutch elements to release their power transmitting clutching engagement with each other and thereby render the transmitter inactive.
13. In a combined motor and power transmitter, the combination of an electric motor and its armature shaft; a driving clutch element actuated by said shaft; a cooperating driven clutch element; spring means carried by one of said elements and acting upon the other element to press the two elements into power transmitting clutching engagement; means acting counter to said spring means to cause said clutch elements to release their power transmitting engagement and thereby render the transmitter inactive and means under control of an operative for rendering said counteracting releasing means ineffective.
14. In a combined motor and power transmitter, the combination of an electric motor and its armature shaft; a driving clutch element carried by and rotatable with said shaft; a cooperating driven clutch element; spring means carried by one of said elements and acting on the other element to relatively move and press said two clutch elements into power transmitting clutching engagement; means acting counter to said spring means to cause said clutch elements to release their power transmitting engagement and thereby render the transmitter inactive and means under control of an operative for rendering said counteracting releasing means ineffective.
15. In a combined motor and power transmitter, the combination of an electric motor and its armature shaft; a driving clutch element carried by and rotatable with said shaft; a cooperating driven clutch element including relatively movable parts one fixed against movement axially of said shaft and the other movable axially of said shaft; a pulley fixed to one of said parts to rotate therewith; a brake including two cooperating members adapted to be moved into and out of engagement with each other one of said members being carried by said part of the drive clutch element which has movement axially of the driving shaft; spring means carried by said driven clutch element and acting to press the same and the driving clutch element into power transmitting clutching engagement with each other; and means causing said clutch elements to release

their said power transmitting clutching engagement and moving the axially movable part of the driven element to engage the brake member thereof with said cooperating brake member.

16. In a combined motor and power transmitter, the combination of an electric motor and its armature shaft; a driving element of a friction clutch rotated by said shaft; a cooperating driven element of the friction clutch; means pressing said clutch elements into power transmitting frictional engagement with each other without creating end thrust to be overcome by the driving power of said shaft while the transmitter is acting to transmit power; and means causing said clutch elements to release their power transmitting frictional engagement with each other and thereby render the transmitter inactive.

17. In a combined motor and power transmitter, the combination of an electric motor and its armature shaft; a driving element of a friction clutch rotated by said shaft; a cooperating driven element of the friction clutch; means pressing said clutch elements into power transmitting frictional engagement with each other without pressure of a non-rotating part against a rotating part to maintain such engagement while transmitting power; and means causing said clutch elements to release their power transmitting frictional engagement with each other and thereby render the transmitter inactive.

18. In a combined motor and power transmitter, the combination of an electric motor and its armature shaft; a driving element of a friction clutch rotated by said shaft; a cooperating driven element of the friction clutch; means pressing said clutch elements into power transmitting frictional engagement with each other without creating end thrust upon said shaft while the transmitter is acting to transmit power; and means causing said clutch elements to release their power transmitting frictional engagement with each other and thereby render the transmitter inactive.

19. In a combined motor and power transmitter, the combination of an electric motor and its armature shaft; a driving element of a friction clutch carried by and rotatable with said shaft; a cooperating driven element of said friction clutch; spring means carried by one of said clutch elements and acting to press the two clutch elements into frictional clutching engagement to transmit power; and means causing said elements to release their power transmitting clutching engagement with each other and thereby render the transmitter inactive.

20. In a combined motor and power transmitter, the combination of an electric motor and its armature shaft; a driving element of a friction clutch carried by and rotatable

with said shaft; a cooperating driven element of said friction clutch; spring means carried by one of said clutch elements and acting to press the two clutch elements into frictional clutching engagement to transmit power; means causing said elements to release their power transmitter clutching engagement with each other and thereby render the transmitter inactive; a pulley rotatable with said driven clutch element; and a brake member carried by said clutch element and adapted to be engaged with a cooperating brake member when the clutch elements are disengaged.

21. In a combined motor and power transmitter, the combination of an electric motor and its armature shaft; a driven clutch element carried by said shaft; a driving clutch element carried by and rotatable with said shaft and movable axially thereof into and out of engagement with said driven clutch element; spring means carried by said driven clutch element and acting upon said driving clutch element to move it axially of said shaft and press it into power transmitting clutching engagement with said driven clutch element; and means acting counter to said spring means to cause said clutch elements to release their power transmitting engagement and thereby render the transmitter inactive.

22. In a power transmitter, the combination of a driving shaft; a driven clutch element carried by said shaft; a driving clutch element carried by and rotatable with said shaft and movable axially thereof into and out of engagement with said driven clutch element; spring means carried by said driven clutch element and acting upon said driving clutch element to move it axially of said shaft and press it into power transmitting clutching engagement with said driven clutch element; and means acting counter to said spring means to cause said clutch elements to release their power transmitting engagement and thereby render the transmitter inactive.

23. In a power transmitter, the combination of a driving shaft; a driving friction clutch element on and connected to said shaft to rotate therewith; a driven friction clutch element including two relatively movable rotatable parts between which the driving element is positioned and adapted to be gripped; spring means carried by said driven element and acting to press the two parts thereof towards each other and into clutching engagement with the interposed driving element; and means acting counter to said spring means to move said two parts of the driven element relatively away from each other and thereby release the clutching engagement of the two clutch elements.

24. In a power transmitter, the combination of a driving shaft; a driving friction

clutch element on and connected to said shaft to rotate therewith; a driven friction clutch element including two rotatable parts between which the driving clutch element is positioned and adapted to be gripped, one of said parts being fixed against axial movement and the other part being axially movable; spring means carried by said driven element and acting to move said axially movable part thereof toward the other part and clutching the driving clutch element between said parts of the driven clutch element; and means acting to move said axially movable part of the driven element away from the other part thereof in opposition to the tension of said spring means and thereby release the clutch.

25. In a power transmitter, the combination of a driving shaft; a driving friction clutch element on and connected to said shaft to rotate therewith; a driven friction clutch element including two rotatable parts between which the driving clutch element is positioned and adapted to be gripped, one of said parts being fixed against axial movement and the other part being axially movable; spring means carried by said driven element and acting to move said axially movable part thereof toward the other part and clutching the driving clutch element between said parts of the driven clutch element; means acting to move said axially movable part of the driven element away from the other part thereof in opposition to the tension of said spring means and thereby release the clutch; and a pulley on said part of the driven clutch element which is fixed against axial movement.

26. In a power transmitter, the combination of a driving shaft; a driving friction clutch element on and connected to said shaft to rotate therewith; a driven friction clutch element including two rotatable parts between which the driving clutch element is positioned and adapted to be gripped, one of said parts being fixed against axial movement and the other part being axially movable; spring means carried by said driven element and acting to move said axially movable part thereof toward the other part and clutching the driving clutch element between said parts of the driven clutch element; means acting to move said axially movable part of the driven element away from the other part thereof in opposition to the tension of said spring means and thereby release the clutch; and a brake having one member thereof on said axially movable part of the driven clutch member adapted to be engaged with a cooperating brake member by the aforesaid axial movement of said part of the driven clutch member to its clutch releasing position.

27. In a combined motor and power transmitter, the combination of an electric motor

and its armature shaft; a friction clutch including a driving clutch element on said shaft and a cooperating driven clutch element; means for causing said clutch elements to be relatively moved into and out of clutching engagement with each other; and a driven pulley positioned about said shaft between the motor and said clutch elements and fixed to the driven clutch element 10 to rotate therewith.

28. In a combined motor and power transmitter, the combination of an electric motor and its armature shaft; a friction clutch including a driving element mounted on said shaft to rotate therewith and a cooperating driven element supported by said shaft and including two relatively movable parts with said driving clutch element interposed between them; means for causing said parts 15 to be relatively moved toward and from each other into and out of clutching engagement with the interposed driving clutch element; and a driven pulley positioned about said shaft between the motor and the clutch elements and fixed to the driven clutch element 20 to rotate therewith.

29. In a combined motor and power transmitter, the combination of an electric motor and its armature shaft; a friction clutch including a driving element mounted on said shaft to rotate therewith and a cooperating driven element supported by said shaft and including two relatively movable parts with said driving clutch element interposed 25 between them; means for causing said parts to be relatively moved toward and from each other into and out of clutching engagement with the interposed driving clutch element; a driven pulley positioned about said shaft between the motor and the clutch elements and fixed to one of said parts of the driven clutch element to rotate therewith; and cooperating brake members one of which is carried by said other part of the driven 30 clutch member to rotate therewith.

30. In a power transmitter, the combination of an enclosing casing; a driving shaft in a chamber within said casing; a driving friction clutch element on and rotating with said shaft in said chamber; a cooperating driven friction clutch element in said chamber; a driven pulley rotatable with said driven clutch element within said chamber; and means controlled from the exterior of 35 said chamber for effecting operative engagement and disengagement of said clutch elements.

31. In a combined motor and power transmitter, the combination of an enclosing casing; an electric motor in one end of said casing with its armature shaft extended toward and into the other end of the casing; driving and driven friction clutch elements and a pulley all located in the other end of 40

the casing with the driving clutch element 45 actuated by said armature shaft at the extended end of the latter and the pulley rotatable with the driven clutch element; and means controlled from the exterior of said casing for effecting operative engagement 50 and disengagement of said clutch elements.

32. In a combined motor and power transmitter, the combination of an enclosing casing including a plurality of sections secured together end to end; an electric motor in 55 one end of said casing with its armature shaft extended toward and into the other end of the casing; driving and driven friction clutch elements and a driven pulley all associated with said extended portion of the 60 armature shaft and located in said other end of the casing; and means controlled from the exterior of said casing for effecting operative engagement and disengagement of said clutch elements.

33. In a power transmitter, the combination of a shaft; a friction clutch including rotatable driving and driven elements adapted to be relatively moved into and out of frictional clutching engagement with each 65 other; a pulley formed of a plurality of sections adapted to fit together and be assembled around a part on one of said clutch elements; and means securing said pulley sections in their assembled relationship on said 70 clutch element and whereby the pulley may be fastened in place or removed without disturbing the assembled relationship of other 75 parts of the mechanism.

34. In a power transmitter, the combination with a rotatable part thereof; of a pulley adapted to be fixed to and rotated with said rotatable part and formed of a plurality of sections adapted to fit together and be assembled around a portion of said 80 rotatable part; and means accessible at the periphery of the pulley and fastening the sections thereof together whereby the pulley may be applied and fastened in place or released and removed without disturbing the 85 assembled relationship of other parts of the mechanism.

35. In a power transmitter, the combination of an enclosing casing; a driving shaft; driving and driven friction clutch elements 90 associated with said shaft within the casing; and a pulley within said casing and secured to one of said clutch elements to rotate therewith said pulley being so constructed and positioned with relation to a slot or 95 opening in the side wall of the casing as to be detachable from the clutch part with which it is rotatable and removable through said opening in the side wall of the casing without disturbing or disassembling other 100 parts of the mechanism.

36. In a power transmitter, the combination with a rotatable part thereof, of a

5 pulley adapted to be fixed to and rotate with said rotatable part and formed of a plurality of sections adapted to fit together and be assembled around a portion of said rotatable part; means accessible at the periphery of the pulley for fastening the sections thereof together; and an enclosing casing having in its wall a slot or opening through which access may be had to said fastening
10 means to apply or release the same and through which opening the pulley sections may be either introduced and assembled in place, or be removed, all without disturbing the assembled relationship of other parts
15 of the mechanism.

17. In a power transmitter, the combination with a rotatable part thereof, of a pulley secured to said rotatable part to rotate therewith; and a larger pulley formed
20 in sections adapted to fit together and be assembled and secured around said first

named pulley when it is desired to use said larger pulley.

38. In a power transmitter, the combination of a driving shaft, a driving friction clutch element on and connected to said shaft to rotate therewith; a driven friction clutch element including two relatively movable rotatable parts between which the driving element is positioned and adapted to be gripped; spring means carried by said driven element and acting to press the two parts thereof towards each other and into clutching engagement with the interposed driving element; and means acting counter to said spring means to move said two parts of the driven element relatively away from each other and thereby release the clutching engagement of the two clutch elements.

In testimony whereof I have signed this 40 specification.

CHARLES R. COLT.
